UNITED STATES PATENT OFFICE.

WATSON EASTMAN, OF PORTLAND, OREGON, ASSIGNOR TO WESTERN COOPERAGE COMPANY, OF PORTLAND, OREGON, A CORPORATION OF OREGON.

WOOD-SPLITTING MACHINE.

Application filed February 25, 1920. Serial No. 361,315.

To all whom it may concern:

Be it known that I, WATSON EASTMAN, a citizen of the United States, residing at Portland, in the county of Multnomah and State of Oregon, have invented a new and useful Wood-Splitting Machine, of which the following is a specification.

This invention relates to wood splitting machines, and particularly to machines of the type which employs gravity to deliver a blow upon a wedge placed on a block of wood.

One object of the present invention is to provide a splitting machine whose splitting head may be swung directly over the wedge whatever the position of the same.

A further object is to provide a machine whose splitting head is under perfect control of the operator which can be raised or lowered to any desired extent and then reversed in direction, and which can be made to deliver a series of light blows in succession, or powerful blows at intervals.

The present machine is used for splitting blocks cut from logs. The blocks are split in any number of pieces by placing wedges at desired points on the end of the block. The frame of the machine is articulated or hinged so that the splitting head may be moved directly over the wedge. If the splitting machine had a rigid and stationary frame it would be necessary to move the block each time so that the wedge would be directly under the splitting head. With the present machine, the articulated frame will allow swinging of the head in any horizontal path to permit its positioning directly over the wedge.

The invention will be best understood from a consideration of the following detailed description taken in connection with the accompanying drawings forming part of this specification with the understanding, however, that the invention is not confined to any strict conformity to the showing of the drawings, but may be changed and modified so long as such changes and modifications mark no material departure from the salient features of the invention as expressed in the appended claims.

In the drawings:—

Figure 1 is an elevation of a practical machine embodying the principles of my invention;

Fig. 2 is a cross section on the line 2—2 of Fig. 1, but on a larger scale;

Fig. 3, is an elevation showing the machine from the splitting head end;

Fig. 4, is an elevation of the parts of the controlling mechanism for the splitting head shown on an enlarged scale;

Fig. 5, is a sectional view on the line 5—5 of Fig. 1;

Fig. 6, is a vertical cross sectional view of the parts illustrated in Fig. 5;

Fig. 7, is a longitudinal cross section of the spur pinion and the friction clutch;

Fig. 8 is a fragmentary elevation with parts in section showing a portion of the driving member of the friction clutch;

Fig. 9, is a elevation of the cup brake;

Fig. 10, is an elevation partly in section of a lever fulcrum;

Fig. 11, is a perspective view of a part of the mechanism which controls the brake and clutch; and

Fig. 12 is an elevation of a slightly modified form of splitting head.

The machine proper is supported upon an upright beam or post 15 so as to swing upon an axis fixed relatively to the post whereby it assumes vertical positions at all times. A cross beam 15^a is also provided to support parts of the driving means. Upon the vertical post 15 a channel bar 16 is mounted with the flanges of the channel bar fitted about the sides of the post. Bolts 17 unite the channel bar and the post. The channel bar has a plurality of brackets 18, 19, 20, outstanding from its outerface for a purpose to be described.

The cross beam 15^a supports a bearing 22, while the channel member 16 supports a thrust bearing 23 in alignment therewith, the bearings 22 and 23 properly supporting a shaft 21 having a band pulley 24 keyed or otherwise secured upon the same. Pulley 24 is connected by belting to any convenient source of power, as an electric motor. An angle bracket 25 is also provided upon the channel member 16 and additionally supports and braces the shaft 21. A bevel gear 26 is fixed upon the shaft 21 between the angle bracket 25 and the bearing 23, and meshes with a bevel gear 27 provided on an upright shaft 28 running longitudinally with the post 15. At the lower end of the shaft 28 a bevel gear 29 is secured.

A frame 30 preferably made of cast steel properly braced is mounted upon the brackets 18, 19, 20, so as to assume vertical positions about an axis passing through said brackets. This frame is provided with a thrust bearing 31 which receives the lower end of the shaft 28. The frame 30 has arms 32, 33 and 34 corresponding to said brackets in the matter of spacing, and co-operating 10 with the same to permit free turning of the frame.

The construction of the hinge parts is best seen in Figs. 5 and 6. While the lowermost of the pivotal elements only is shown in 15 these figures, the construction of the two upper pivotal parts is almost precisely the same. The arm 32 has a T-head 32^a, to which is secured a bar 35 by means of bolts or studs 36. A pivot pin 37 is passed through 20 the bracket 18, a bushing 39 being interposed therebetween. The pin 37 has heads 38 at either end, holding it in place. The bushing 39 has an annular flange 40 at its upper end provided with a circumferential recess or 25 groove on the top face thereof, to receive ball bearings 40^a, which are also received in a similar circumferential recess provided in the under part of the head 32^a and the bar 35. The frame 30 is thus freely turnable 30 upon the pin 37 as an axis. The connection between the upper brackets 19, 20, and the arms 33, 34, is the same as that described for the lower brackets 18 and the arm 32, except that instead of having a pivot pin 37 the 35 shaft 28 is utilized as a pivotal element. On this account it is deemed unnecessary to disclose each connection in detail. Any other form of ball bearing hinge may be used.

A horizontal shaft 42 turns within bearings 40 provided in the frame 30 and has a bevel gear 41 at its inner end meshed with the bevel gear 29, while at its outer end it is provided with a bevel gear 43. The frame 30 is further provided with arms 44 and 45 in horizontal alignment respectively with the arms 32 and 33 above mentioned. An auxiliary frame 47 having arms 48 and 49 is pivoted to the frame 30 by means of pins 46 engaging with the hinge arms 44, 45, 48 and 50. Thus the frame 47 is pivoted upon the frame 30, which, in turn, is pivoted upon a fixed support, and both the main and auxiliary frames swing about independent vertical axes.

The auxiliary frame 47 is provided with a bearing 50 having a shaft 51 which is also held by a bearing 52 provided on the frame 30. The shaft 51 is held in a vertical position in alignment with the pivot pins 46. The upper end of the shaft 51 has a bevel gear 53 meshing with the bevel gear 43, while the lower end of the shaft 51 has a bevel gear 54. A horizontal shaft 55 is supported upon the auxiliary frame 47 by means of a bearing 56 at the inner end of the

frame and a bearing 71 at the outer end of the frame. The inner end of the shaft 55 has a bevel gear 57 meshing with gear 54.

The frame 47 is further provided with ears 58 intermediate its ends and similar 70 ears 59 near its outer end. The upper pair of ears 58, 59, receives a rod 60 in apertures provided in the ears, while the lower pair of ears 58, 59 receives a similar but shorter rod 61 in apertures. Set screws 62 are provided for the lower pair of ears and set screws 63 are provided for the upper pair of ears, whereby rods 60 and 61 may be clamped in proper positions.

A cup brake 65 (see Fig. 9) having a pair 80 of ears 68 is slidably mounted upon the rods 60 and 61 by means of said ears, a lining of babbitt 69 being provided to reduce friction. Coil springs 64 mounted on the rods 60 and 61 urge the cup brake in the direction of 85 the clutch to be described. The cup brake has pins 66 for connection with parts to be described. Where the pins 66 protrude from the sides of the cup brake its surface is preferably flattened as indicated at 67. The cup 90 brake has a central tapered or frusto-conical aperture of sufficient diameter to fit over the outside of the driven part of the clutch. A brake lining 70 is provided upon the cup 95 brake to engage upon the outer part of the clutch member.

As is seen best in Figs. 7 and 8, the clutch comprises a cone friction 76 and a cup friction 75, the latter being integral with a spur pinion 72. The spur pinion has teeth 100 73 to engage with a rack, in turn made fast to the splitting head as will be described. A bushing 74 is mounted upon the shaft 55 concentric with the spur pinion 72. The spur pinion is designed to turn upon the shaft 55 105 only when the cone friction is engaged with the cup friction, as shown in Fig. 7.

The cone friction 76 has a paper cone 77 held upon the same by means of a ring 78 and studs 79. The cone friction is secured 110 upon the shaft 55 by means of a key 81 and has an appropriate keyway adapted to receive said key. Thus it is seen that the cone friction turns whenever the shaft 55 is revolved, while the cup friction and consequently the spur pinion only turns when the cone friction is moved into engaging position. The end of the cone friction opposite to or remote from the engaging end is provided with a boss 82 having external 115 screw threads 83. A plate or disk 84 is secured to the cone friction by means of these screw threads. A clutch collar 85 is mounted upon the boss 82 and is held to the cone friction by means of the disk or plate 84. The threads 83 are so arranged that the rotation of shaft 55 which carries with it the plate 84 will tend to tighten said plate.

As seen in Fig. 11 the clutch collar 85 has a central aperture or bore 87 adapted to 120

fit over the boss 82 to allow free rotation of the cup friction relatively to the clutch collar. The latter element is also provided with pins 86 to which links 88 are pivotally secured. Levers 89 are pivoted upon either end of a lever fulcrum 92, and are connected intermediate their ends with the links 88, whereby the swinging of the levers 89 moves the clutch collar and with it the cone friction. Upon the levers 89 are also secured adjustable links 90, preferably by the same means which connect links 88 to said levers. The adjustable links 90 are connected at their opposite ends to the cup brake 65 by means of the pins 66 above mentioned.

The lever fulcrum 92, as stated, supports at either end one of the levers 89, and in turn is secured upon the rod 60 by means of an ear 93 and set screw 94. The other ends 20 of the levers 89 are pivotally connected with adjustable links 91, similar to the adjustable links 90. Each link 91 is connected with a bell-crank lever 95 mounted upon the frame 47.

25 The bell-crank lever 95 comprises an arm 96^a, a second arm 96^b at right angles thereto, a bridge plate 97, and an arm 98 parallel to arm 96^a and connected therewith by the bridge-piece 97. Aligned apertures 99 and 30 100 in the bell-crank lever permit pivoting of the same upon the frame 47. The outer end of arm 96^b is pivotally connected with a rod 101 which passes through a web or the like provided on the frame 47 and is secured at its outer end to an operating or hand lever 106. A coiled spring 107 is held upon the rod 101 between the frame 47 and the hand lever and operates to normally hold the hand lever in the position illustrated in Figs. 1 and 4, in which position the clutch is disengaged and the brake is set.

40 A rod 102 is fixed in upright position to the rods 60 and 61 by connecting elements 103 and 104 respectively. This rod 102 provides convenient means by which the hammer head may be guided to a position directly above the wedge. Upon the rod 102 and between the elements 103 and 104 a lever fulcrum 105 is secured and to said lever ful-

50 crum the hand lever 106 is connected.

A bracket 108 is provided on the side of the frame 47 opposite to that which appears in Figs. 1 and 4, and serves as a supporting means for a plurality of guide rollers 55 109 which are spool-shaped, as shown in Fig. 2. The guide rollers 109 direct a gear rack 110 in vertical movements relatively to the frame of the machine. The gear rack 110 is provided with beveled edges 111 running longitudinally therewith and fitting into the spool-shaped guide rollers 109. The gear rack has teeth 112 running the entire length thereof and designed to mesh with the teeth 73 of the spur pinion 72.

65 The lower end of the gear rack is pro-

vided with a taper pin 113 received in a correspondingly shaped bore provided in a hammer head 114. The hammer head 114 has a transverse bore 115, and a pin 116 is run through the lower end of the taper pin 70 113 and holds the taper pin and hammer head in assembled relation.

Instead of this construction the gear rack may, as shown in Fig. 12, be fashioned into one piece with a hammer head 117. In this case, the hammer head and the gear rack 75 118 are cast at the same time and need no assembling.

It will be observed that the driving shaft is broken into five parts connected together by bevel gears. The arrangement is such that the driving speed of the pulley 24 is largely reduced, while the free turning of the hinged sections of the frame is permitted when the shafts are rotating.

80 The machine operates as follows. The start is made with the hammer head in its uppermost position with the brake on, holding the head stationary. The hand lever is in the position shown in the drawings, 85 which is its uppermost position. The clutch is disengaged, which is always the case when the brake is engaged. It is desired to allow the hammer head to fall. The hand lever is moved down slightly which releases the 90 brake to allow the head to drop by gravity. This slight movement of the hand lever is not sufficient to force the members of the clutch into engagement. The hammer head having delivered its blow upon the wedge 95 the next step will be to raise it. To do this, the lever is moved down further in the same direction. This engages the clutch and the head is run up by the turning of the spur pinion in engagement with the rack. When the head has reached its uppermost position and it is desired to stop its movement and hold it in place the hand lever is pulled or released to move upwardly, which again 100 disengages the clutch and applies the brake.

105 If it had been desired to raise the hammer head and drop it instantly without holding it in its upper position, it would only have been necessary to pull the hand lever down a sufficient distance to engage the clutch and then quickly pull the lever in the opposite direction to disengage the clutch, without throwing on the brake.

110 What is claimed is:—

115 1. In a wood splitting machine, a support having a plurality of brackets spaced apart, a vertical power driven shaft passed through two of said brackets, a hinged frame having a plurality of supporting arms resting upon said brackets, a separate pivot connecting one of the arms with one of the brackets, the other arms turning on said shaft, wedge driving means mounted upon said frame, and means including said shaft for elevating 120 said driving means.

2. In a wood splitting machine, a support, a hinged frame made up of a plurality of hingedly connected members, the innermost member being pivoted on the support, a hammer head mounted to reciprocate in a vertical direction on the outermost frame, the hinged connections of said frame members permitting the head to be moved in or out towards or from said support in a horizontal plane without affecting the vertical position of said head, a horizontal shaft on the outermost frame, gearing between said shaft and said hammer head, a vertical shaft in the axis of the pivotal connection between the outermost frame and the next adjacent frame; a horizontal shaft mounted on the innermost frame, a second vertical shaft to which the innermost frame is pivoted, means for connecting the second vertical shaft to a source of power, and gearing between the second-mentioned vertical shaft, the second-mentioned horizontal shaft, the first-mentioned vertical shaft, and the first-mentioned horizontal shaft to actuate the hammer head.

3. In a wood splitting machine having a reciprocable hammer head, an operating lever, and means interposed between and connected to the hammer head and lever whereby when the lever is in its normal position, the hammer head is maintained stationary and when the lever is moved out of its normal position, the hammer head is allowed to fall by gravity, and when the lever is moved still farther in the same direction, the hammer head is raised by a source of power.

4. In a wood splitting machine, a hinged frame, a hammer head reciprocable on the frame, horizontal rods fixed upon the frame in substantially parallel relation, a friction brake slideable on said rods, means for imparting to the brake a tendency to move in one direction along the rods, means fixed upon the rods for guiding the hammer head, and brake-releasing means supported upon the frame and upon said guiding means.

5. In a wood splitting machine, a frame, a reciprocable hammer head mounted upon the frame, a pair of spaced substantially parallel rods fixed upon the frame, a brake slidably held upon the rods, springs for normally impelling the brake in one direction, said brake normally holding said hammer head stationary, an operating lever, mechanism interposed between the operating lever and the brake whereby movement of the lever will release said brake and the hammer head, and a spring normally holding the operating lever in braking position.

6. In a wood splitting machine, a frame, a reciprocable hammer head mounted upon said frame, a driving shaft rotatable upon the frame, a clutch interposed between the driving shaft and the hammer head, a brake mounted upon the frame and engageable

with the driven member of the clutch, and means for releasing the brake and engaging the clutch, said means operating first to release the brake and then engage the clutch, the operating means at a predetermined point between the brake releasing position and the clutching position being adapted to release the hammer head.

7. In a wood splitting machine, a frame, a reciprocable hammer head mounted upon the frame, a rack secured to said hammer head to fall therewith, a driving shaft also mounted upon the frame, a clutch interposed between the driving shaft and the reciprocable head, said clutch comprising a cone friction and a cup friction, the cone friction being secured upon said driving shaft and the cup friction being mounted loosely upon the same shaft, and a pinion formed integrally with the cup friction, said pinion engaging with the rack.

8. In a wood splitting machine, a frame, a reciprocable hammer head mounted upon the frame, a driving shaft mounted upon the frame, a clutch interposed between the driving shaft and the reciprocable head, a brake slideable upon the frame and normally engaging with the driven member of the clutch to hold the hammer head, said brake including an annular member surrounding the driven member of the clutch and designed to engage frictionally with the outer walls of the same, the inner engaging part of the brake being provided with a brake lining.

9. In a wood splitting machine, a supporting frame hinged at two places, a reciprocable hammer head mounted upon the frame, a guiding rod secured upon the frame whereby the reciprocable hammer head may be placed directly over the work without moving the same, and mechanism for engaging the reciprocable head with a source of power to release the same to fall by gravity, or to hold the same at any desired point, said mechanism operating by means of a hand lever, movement of the hand lever in one direction first releasing the hammer head and second raising the same, the movement of the lever in the opposite direction checking the movement of the hammer head and holding the same stationary.

10. In a wood splitting machine, a frame, a reciprocable hammer head mounted upon the frame, a driving shaft mounted upon the frame, a clutch interposed between the driving shaft and the reciprocable head, a brake normally engaging with the driven member of the clutch, rods on the frame upon which said brake is slidably mounted, springs mounted upon said rods for causing said brake to move in one direction along said rods, and a hand-actuated lever connected to the brake for moving the same along said rods against the force of said

springs said lever being connected to said clutch to engage the same after the brake has been released.

11. In a wood splitting machine, a frame, 5 a reciprocable hammer head mounted upon the frame, a driving shaft mounted upon the frame, a clutch interposed between the driving shaft and the reciprocable head, a brake normally engaging with the driven member of the clutch, springs for causing said brake to move in one direction, and a hand-actuated lever connected to the brake for moving the same against the force of said springs, said lever being connected to 10 said clutch to engage the same after the brake has been released, and to throw both the clutch and brake into neutral to release the hammer head when said head is in an elevated position.
12. In a wood splitting machine, in combination, a frame, a hammer head, a reciprocable rack mounted upon the frame and connected to the hammer head to fall therewith, a pinion meshing with the rack, a 15 brake for holding the pinion from rotation whereby the rack may be held stationary at any desired point in its path, and manually operable means for releasing the brake to allow the hammer head to fall, and for engaging the pinion with a source of power to 20 raise the head.
13. In a wood splitting machine, in combination, a frame, a hammer head, a reciprocable rack mounted upon the frame and 25 secured to the hammer head to fall therewith, a pinion meshing with the rack, a

clutch comprising a driving and a driven member, the driving member being connected to a source of power and the driven member being joined to the pinion, and operator controlled means for engaging the clutch members to raise the hammer head. 40

14. In a wood splitting machine, in combination, a frame, a hammer head, a reciprocable rack mounted upon the frame and 45 secured to the hammer head to fall therewith, a pinion meshing with said rack, a clutch comprising a driving member which is connected with a source of power and a driven member which is secured to the 50 pinion, a brake engaging with the driven member of the clutch, and means for engaging the clutch members to raise the hammer head and for controlling the brake.

15. In a wood splitting machine, in combination, a frame, a reciprocable hammer head mounted upon the frame, a driving shaft rotatable upon the frame, a clutch interposed between the driving shaft and the hammer head, a brake mounted upon the 55 frame and engageable with the driven member of the clutch, manually operated means connected to the brake and clutch and adapted first to release the brake, then to pass into a neutral position, and finally to 60 engage the clutch, and a spring mounted so as to hold said means in brake setting position.

In testimony that I claim the foregoing as my own, I have hereto affixed my signature. 70

WATSON EASTMAN.
